(57) **CLAIM**

The ornamental design for a cam switch, as shown and described.

DESCRIPTION

FIG. 1 is a perspective view of a cam switch showing our new design.

FIG. 2 is a front elevational view thereof.

FIG. 3 is a rear elevational view thereof drawn at a larger scale for ease of illustration.

FIG. 4 is a left side elevational view thereof.

FIG. 5 is a right side elevational view thereof.

FIG. 6 is a top plan view thereof.

FIG. 7 is a bottom plan view thereof; and,

FIG. 8 is an enlarged bottom plan view of the lower end unit shown in FIG. 7 drawn at a larger scale for ease of illustration. The broken line showing of the cam switch is for the purpose of illustrating environmental structure and forms no part of the claimed design.
